UNITED STATES PATENT OFFICE

112,400

DESIGN FOR A LIP STICK HOLDER

Irene Penn, New York, N. Y., assignor to Hattie Carnegie, Inc., a corporation of New York

Application June 30, 1938, Serial No. 78,185

Term of patent 7 years

To all whom it may concern:

Be it known that I, Irene Penn, a citizen of the United States, residing in New York city, in the county of New York, in the State of New York, have invented a new, original, and ornamental Design for a Lip Stick Holder, of which the following is a specification, reference being had to the accompanying drawing, forming part thereof:

I claim:

The ornamental design for a lip stick holder, substantially as shown.

IRENE PENN.
